METAL SHIPPING CONTAINER

John M. Hothersall, Brooklyn, N. Y., assignor to
 American Can Company, New York, N. Y., a
 corporation of New Jersey

Application February 20, 1931, Serial No. 517,246

5 Claims. (Cl. 220—72)

The present invention relates to a metal shipping container and has particular reference to a rectangular container for oil and gasoline and other products which is formed to prevent fracture and buckling of parts during shipment.

The principal object of the present invention is the provision of a container having rectangular flat side wall panels outlined by drawn or pressed-out sections of a castellated and indented pattern, these drawn sections, by reason of their shape and relative positions providing a flexibility in the can walls which insures a maximum of protection to the container by allowing sloshing of its liquid contents, with its resulting wall movement, without fracture or buckling.

Numerous other objects of the invention will be apparent as it is better understood from the following description, which, taken in connection with the accompanying drawing, discloses a preferred embodiment thereof.

Referring to the drawing:

Figure 1 is a perspective view of a rectangular container embodying the present invention;

Fig. 2 is a fragmentary sectional view taken substantially along the line 2—2 in Fig. 1;

Fig. 3 is a sectional view of one of the side walls of the container being taken substantially along the line 3—3 in Fig. 1; and

Fig. 4 is a similar section taken substantially along the line 4—4 in Fig. 1.

The shipment of oil products by boat is a large industry and a favorite package for the product is a rectangular, relatively light gage sheet metal container usually of five-gallon capacity. Such a container preferably has its side walls paneled to enhance its appearance and to provide space for labels, stickers, etc., and decorative embellishments.

The swaying motion of the ship, loaded with these containers, piled one on top of the other and often in several layers in the hold of the vessel, causes considerable sloshing and splashing of the liquid contents against the interior walls of containers.

This results in repeated flexing of the container walls and a bending back and forth of the metal thereof. Such repeated bending of the metal if concentrated adjacent a sharp edge as of a bead or sharp-cornered drawn section, often causes a fracture at that point permitting the liquid contents to run out and become lost and at the same time establishing a fire and explosive hazard. These fractures are particularly prevalent at parts of the can which may have become dented or bent in handling, such a dent soon

developing a fracture if adjacent a stiff ridge or bead in the can wall.

The present invention relates to an improved container of this general character provided with zones of flexure and one wherein continuous stiffening beads or sharp-cornered wall sections are omitted. This improved container has the necessary panels but its walls are so formed that they may be repeatedly flexed without fracture. Such a container is properly strengthened to resist the forces tending to buckle or collapse it but is so designed as to permit movement of even dented and bent sections without such concentration of sharp bending movements as to cause fracture. This will become more evident as the description proceeds.

Such an improved container comprises a rectangular container body 11 having side walls 12 joined by corners 13 produced by the bending of the metal in the formation of the container. The container body 11 is closed by end members 14 secured thereto by double seams.

Each side wall 12 is struck outwardly in a series of projecting tongues 15 which are arranged along the margin of the side and around a central panel 16. The outer faces of the projections 15 are in a single plane, as illustrated in Fig. 3, which is spaced slightly beyond the outer face of the panel wall 16. These projections 15 lie closely adjacent one another and form an indented pattern having zones of flexure intermediate thereof. This construction strengthens the corners 13 in a vertical direction and provides a flexing or yielding characteristic to the entire wall structure.

Each end 14 may be reinforced by a series of projecting panels 17 of suitable configuration, the outer faces of which lie in one plane as shown in Fig. 2 and these also allow flexing throughout without sharp bends.

This construction of the container permits stacking one on top of another and their rectangular form affords close packing without waste space. The patterned side walls can yield under the swaying motion of the ship and diagonal, vertical and horizontal thrusts imposed thereby are readily compensated by the proper body movement. There being no sharp stiff edges nor lines of fold along which flexing of the metal is concentrated, the dangers of fractures and buckling are eliminated.

The containers may be filled in any suitable manner, a filling opening 18 formed in the top end being used for this purpose. This may be closed in the usual way by a soldered cap.

55

It is thought that the invention and many of its attendant advantages will be understood from the foregoing description, and it will be apparent that various changes may be made in the form, 5 construction and arrangement of the parts without departing from the spirit and scope of the invention or sacrificing all of its material advantages, the form hereinbefore described being merely a preferred embodiment thereof.

10 I claim:

15 1. A rectangular sheet metal container the side walls of which are embossed inwardly to form a central panel, leaving outwardly raised marginal portions, and, extending from said marginal portions toward the middle of the panel, spaced-apart projections which remain in the plane of the marginal portions and have between them depressed parts which are in the 20 plane of the panel, thereby making discontinuous the edges of the panels and strengthening the side walls of the container against fracture along said edges.

25 2. A rectangular container of sheet metal comprising, a body having a plurality of side walls, ends secured to said body, the material of the side walls being bent at intervals adjacent the vertical corners of the container to provide a central side wall panel and pressed side wall edge 30 portions separated from each other and closely spaced together and forming an indentured pattern, the outwardly pressed parts of the pattern merging into the corner portions, and the in-

wardly pressed parts merging into the central part of the wall.

3. A rectangular container comprising a body having a plurality of side walls and ends secured to said body, the marginal portion of said side walls adjacent and between its corner portions being pressed inwardly at spaced intervals to provide a pattern integral with and extending inwardly of the body wall and the outer portion of said pattern merging into the plane of the side 10 walls to provide a predetermined zone of flexure.

4. A rectangular container comprising a body having a plurality of side walls and ends double seamed to the side walls, said side walls being pressed into an inwardly projecting marginal 15 castellated and indentured pattern integral with and disposed adjacent the vertical and horizontal corners and the double seamed ends, the outer portion of said pattern being in the plane of the body wall, to allow for flexing movement 20 of the body wall and to prevent concentration of rupturing strains and sharp bending of the metal thereof.

5. A rectangular metal container the side walls of which are formed with a central panel, and 25 series of inwardly projecting tongues spaced apart and surrounding the panel and constituting an integral part thereof, the bases of said tongues being merged with and in the plane of the metal of the corner portions of the container, to 30 strengthen the corners and give flexibility to the walls, and guard against fracture.

JOHN M. HOTHERSALL.
